UNITED STATES PATENT OFFICE.

BENJAMIN F. WHEELER, OF DETROIT, MICHIGAN, ASSIGNOR TO THE
WHEELER SADDLE CO., OF SAME PLACE.

DESIGN FOR A BICYCLE-SADDLE.

SPECIFICATION forming part of Design No. 25,589, dated June 2, 1896.

Application filed August 29, 1895. Serial No. 560,935. Term of patent 7 years.

To all whom it may concern:

Be it known that I, BENJAMIN F. WHEELER, a citizen of the United States, residing at Detroit, county of Wayne, and State of Michigan, have invented and produced a new and original Design for Bicycle-Saddles, of which the following is a specification, reference being had to the accompanying drawings, forming a part thereof.

10 This invention relates to a new and original design for bicycle-saddles; and it consists in the formation and contour illustrated in the accompanying drawings, in which—

15 Figure 1 is a plan view of my design for a bicycle-saddle cover. Fig. 2 is a section thereof on the line 2 2 of Fig. 1.

20 The leading feature of my design consists in the general shape or configuration of the saddle, as shown in the accompanying illustration.

25 The back of the saddle describes two eccentric semicircular curves A, which start from a depression *b* in the center at the back of the saddle and curve outwardly and forwardly in opposite directions, their outer ends terminating on opposite sides approximate a

line bisecting the longitudinal center of the design, from which point the line of the curves reverse, as at B, and extend sharply inward and forward, converging at the point 30 or nose C of the saddle, which stands but slightly in advance of the curves B and nearly at right angles to the point of junction of said curves with the curves A.

Dividing the saddle centrally is a concavity 35 D, oval in form, which extends longitudinally from a point approximate and in line with the depression *b* at the back to a point approximate the nose of the saddle and between the lines of the curves B, presenting a design 40 of original and peculiar shape.

Having thus fully set forth my invention, what I claim is—

45 The design for a bicycle-saddle substantially as herein shown and described.

In testimony whereof I affix my signature in presence of two witnesses.

BENJAMIN F. WHEELER.
